BILLIARD TABLE OR THE LIKE

George E. Schaefer, Muskegon, Mich., assignor to Brunswick Corporation, Chicago, Ill., a corporation of Delaware

Filed Jan. 22, 1968, Ser. No. 10,256

Term of patent 14 years

Int. Cl. D21—03

U.S. Cl. D34—3

FIG. 1 is a side elevational view of a billiard table or the like embodying my new design, and illustrating two legs in side elevation;

FIG. 2 is an end elevational view thereof illustrating the outer side of a leg; and

FIG. 3 is an enlarged sectional view taken generally along line 3—3 of FIG. 2.

The characteristic feature of my new design for a billiard table or the like resides in the leg portions shown in full lines.

I claim:

The ornamental design for a billiard table or the like, substantially as shown and described.
